UNITED STATES PATENT OFFICE.

GEORGE A. BOYDEN, OF BALTIMORE, MARYLAND, ASSIGNOR TO THE BOYDEN POWER BRAKE COMPANY OF BALTIMORE CITY, OF MARYLAND.

STEAM-VALVE.

SPECIFICATION forming part of Letters Patent No. 394,532, dated December 11, 1888.

Application filed August 10, 1888. Serial No. 282,396. (No model.)

To all whom it may concern:

Be it known that I, GEORGE A. BOYDEN, a citizen of the United States, residing at Baltimore, in the State of Maryland, have invented 5 certain new and useful Improvements in Steam-Valves; and I do declare the following to be a full, clear, and exact description of the invention, such as will enable others skilled in the art to which it appertains to make and use 10 the same, reference being had to the accompanying drawings, and to the letters and figures of reference marked thereon, which form a part of this specification.

My invention relates to improvements in 15 that class of steam-valves that are employed on steam-pumps and like engines of reciprocating movement, whereby steam is alternately admitted or released from one side of the steam-piston or the other by the automatic movement of the valve without the aid 20 of an eccentric or any external valve-gearing; and it consists of certain devices whereby no dead-points will be permitted to the steam-piston, and whereby the entire mechanism of 25 the engine may be incased and protected from dust and other exterior influences, all of which I accomplish by the devices hereinafter fully described and claimed, reference being had to the accompanying drawings, in which—

30 Figure 1 shows a side elevation of a vertical air-pump in full. Fig. 2 shows a vertical section, somewhat enlarged, taken centrally through the steam-cylinder and steam-chest.

The same figures refer to the same or similar parts throughout the several views.

35 The number 4 denotes a vertical steam air-pump, which is provided with this device, the steam-cylinder 5 and the pump-cylinder 6 thereof being connected by the tie-frame 7, 40 the piston-rod 8, moving in the stuffing-boxes 9, being continuous and uniting the air-pump piston to the steam-piston 10, whereby they will be caused to move in unison. Attached to one side of the steam-cylinder is the cylindrical valve-chest 11, which is provided with 45 suitable heads, and has therein the openings 12 and 13, which communicate, through the steam-ports 14 and 15, with the interior of the steam-cylinder, respectively, at either end 50 thereof, an opening, 16, serving to admit the live steam into the interior of the valve-chest.

To control the admission or release of the steam on either side of the steam-piston 10, the valve-chest 11 has therein the piston-valve 17, the heads of which are of differential areas, the valve-chest being provided at each end with different bores, in which moves, respectively, the larger head, 18, or the smaller head, 19, of the said piston-valve, the said two heads being connected by the stem 20, the 55 smaller head, 19, being placed at the bottom of the valve-chest, and each of the said piston-heads having therein the encircling exhaust-recess 23 24, which communicates through a suitable chamber with the atmosphere, suitable packing-rings, 22, being placed around the piston-heads to render this recess 23 and other parts steam-tight.

As stated, the piston-valve 17 is to admit and release the steam on one side of the steam-piston 10 or the other, which is accomplished by the vertical movement of the piston-valve, whereby the ports 12 and 13 will be opened to the steam or to the exhaust-recess 23 24.

As shown in Fig. 2, the steam-piston is at 50 half-stroke and the piston-valve 17 centrally over the openings 12 and 13, in consequence of which all communication with the steam-cylinder is cut off. When steam is admitted to the valve-chest through the opening 16, the 55 pressure thereof will act upon the inner surfaces of the piston-heads 18 and 19, and in consequence of the larger area of the upper head, 18, the piston-valve 17 will be moved upward past the opening 12, through which 60 the steam will pass into the port 14 and exert its pressure on top of the steam-piston 10, this upward movement of the piston-valve 17 having caused the inner part of the lower or smaller piston-head, 19, to move in that direction past the port 13, and open communication with the steam-port 15 and the exhaust-recess 23 in the said piston-head, thus 65 releasing the pressure on the bottom side of the steam-piston 10, which will find escape to 70 the atmosphere through the exhaust-port 21, the reverse or downward movement of the piston-valve 17, by the devices which will shortly appear, causing the pressure to be admitted on the under side of the steam-piston 75 through the opening 13 and the steam-port 15, and released from the upper side thereof.

through the steam-port 14, the opening 12, the exhaust-recess 24, and exhaust-port 21.

In order to impart to the piston-valve 17 the reciprocating movement described, the following devices are employed, whereby live steam from the valve-chest will perform this function. Within the steam-cylinder casting are formed the auxiliary and independent ports 26 and 27, which, respectively, form a communication with the center of the valve-chest and the ends thereof, whereby pressure may be admitted or released by the auxiliary valve 28 to the outer chambers, 51 or 52, around the said piston-heads 18 and 19, and act upon the outer surfaces thereof, the said auxiliary valve 28 having therein the exhaust-ports 32 and 33, which operate with the auxiliary exhaust-port 53 that is formed in the steam-cylinder casing, to release the pressure from one or the other side of the piston-valve 17. To impart movement to the auxiliary valve 28, whereby steam may be admitted or released from the outer sides of the piston-valve, a rod, 29, is passed through that part of the steam-cylinder casting which forms the walls of the steam-ports thereof, the said rod being placed in the plane drawn through the axis of the steam-cylinder and the valve-chest, and free to be moved the required distance parallel with the movement of the steam-piston 10, this rod 29 being provided with a suitable collar, 30, which is straddled by the projecting arms 31 of the auxiliary valve 28, and which is free to be moved in the auxiliary exhaust-port 53, whereby the said rod 29 and the auxiliary valve 28 will be caused to move in unison and the said valve 28 caused to travel over the auxiliary ports 26 and 27, for the purpose described. To impart movement to the rod 29, there is provided on the ends thereof the tappets 34, which project sufficiently far into the cylinder to be touched and moved by the steam-piston 10, a suitable recess being formed in the cylinder-heads to permit this movement.

The manner of operating is as follows: In Fig. 2 the steam-piston is shown at half-stroke and the valves at mid-gear. Steam being admitted through the opening 16, the pressure will act upon the inner surfaces of the piston-heads 18 and 19, and in consequence of the greater area of the upper head, 18, the valve will be moved upward past the opening 12 and open the steam communication through the port 14 to the top of the steam-piston, in consequence of which the steam-piston 10 will move downward until it comes in contact with the lower tappet, 34, when the said tappet will be moved in unison therewith and cause the auxiliary valve 28 to be moved downward past the port 26, through which steam will be admitted from the center of the valve-chest, therein pass around the upper piston-head, 18, into the chamber 51, and act upon the upper surface thereof, the downward movement of the auxiliary valve 28 having opened communication with

the lower auxiliary port, 27, and the exhaust-chamber 32 of the valve 28, through which the pressure from the lower side of the lower piston-head, 19, will be released and escape into the atmosphere through the exhaust-opening 53; and in consequence of this unbalanced pressure on the piston-valve 17 it will be moved downward, the inner edge of the lower piston-head, 19, moved past the opening 13, and steam will be admitted to the under side of the piston 10, and the steam on the upper side of the piston 10 released through the recess 24, which has been opened thereto by the downward movement of the said piston-valve 17, thus causing the piston-valve 17 to be moved up or down by steam-power as the steam-piston 10 comes in contact with the tappets 34 at either end of the steam-cylinder.

From the construction of the device it will be seen that there are no dead-centers to the steam-piston and no point but from which the engine may be started when steam is admitted to the piston-valve 17, which, in consequence of the differential areas of the heads thereof, will always be moved upward when steam is first admitted thereto and cause the steam-piston to descend until in contact with the tappet 34, when the piston-valve will be reversed and the reciprocating movement made continuous.

Having described my invention and the manner of operating, what I claim, and desire to secure by United States Letters Patent, is—

1. In combination with the cylinder 5 and main piston 10, the main valve 17, consisting of differential piston-heads 18 and 19, and the slide-valve 28, actuated by the movements of the main piston and arranged to alternately admit and release the steam-pressure to and from the outer surfaces of the main valve, for the purpose set forth.

2. In combination with the cylinder 5 and main piston 10, the main valve 17, consisting of differential piston-heads 18 and 19, and a slide-valve, 28, placed between the said piston-heads 18 and 19 and arranged to alternately admit and release the steam-pressure to and from the outer surfaces of the main valve, for the purpose set forth.

3. In combination with the cylinder 5 and main piston 10, the main slide-valve 17, consisting of differential piston-heads 18 and 19, a slide-valve, 28, arranged to alternately admit and release the steam-pressure to and from the outer surfaces of the main valve, and a rod, 29, with tappets 34 thereon, for imparting movement to the said slide-valve 28, for the purpose set forth.

4. In combination with the cylinder 5 and main piston, the main valve 17, consisting of the differential heads 18 and 19, a valve-chamber in which moves the said main valve 17, and wherein are formed by the said main valve 17 a central and two outer chambers, ports connecting, respectively, the said central chamber with the two outer chambers,

and a slide-valve, 28, whereby the steam-pressure may be alternately admitted and released through the said ports, for the purpose set forth.

5 5. In combination with a cylinder, 5, and main piston 10, the main slide-valve 17, consisting of the differential heads 18 and 19, a slide-valve, 28, placed between the said heads 18 and 19 and arranged to alternately admit 10 and release the steam-pressure to and from the outer surfaces of the said main valve 17, and a rod, 29, with the tappets 34 thereon,

for imparting movement to said main valve 17, the said rod 29 being placed between the said slide-valve 28 and the main piston 10 15 and operated by the said main piston, for the purpose set forth.

In testimony whereof I affix my signature in presence of two witnesses.

GEORGE A. BOYDEN.
